UNITED STATES PATENT OFFICE.

RUSSEL G. WOODWARD, OF WAUKEGAN, ILLINOIS, ASSIGNEE TO UNION SPECIAL
MACHINE COMPANY, OF CHICAGO, ILLINOIS, A CORPORATION OF ILLINOIS.

THREAD-CONTROLLER FOR SEWING-MACHINES.

1,136,748.

Specification of Letters Patent. Patented Apr. 20, 1915.

Application filed May 11, 1908. Serial No. 432,003.

To all whom it may concern:

Be it known that I, RUSSEL G. WOODWARD, a citizen of the United States, residing at Waukegan, in the county of Lake, State of Illinois, have invented certain new and useful Improvements in Thread-Controllers for Sewing-Machines, of which the following is a description, reference being had to the accompanying drawing and to the letters and figures of reference marked thereon.

My invention relates to new and useful improvements in overseaming machines, and more especially to the three thread type, that is, a machine in which a needle co-operates with a threaded looper beneath the work support, which in turn co-operates with a second threaded looper, which carries its thread over the work support into a position for the needle to enter into a loop formed therein. It will be obvious however, that from certain aspects of my invention, parts thereof at least are useful in connection with other types of machines, and also useful in connection with other elements of the stitch forming mechanism of the present type of machine.

The object of my invention is to provide an overseaming machine wherein a very tight overseam may be made. In making what is known in the trade as a pocket or in finishing the edge of the tongue of a shoe and in common work of a similar character, it is found desirable to make an overseam which shall cover very tightly the edge of the article being stitched.

In carrying out my invention, I have provided a controller for the needle thread which is so arranged as to pull up the slack in the needle thread on the first part of the down stroke of the needle, and to release the needle thread as the needle point is entering the fabric.

I have also further provided means for pulling off thread for the thread carrying looper cooperating with the needle beneath the work support, which pull off also aids in drawing tight the overseaming stitch.

My invention consists in the parts arrangements and improvements hereinafter described and set forth in the appended claims.

In the drawings which show by way of illustration, one embodiment of my inven-

tion; Figure 1 is a side view of a sewing machine with my improvements applied thereto, and with the cover plate removed so as to show certain parts of the stitch forming mechanism. Fig. 2 is a sectional view through the overhanging arm, and the needle lever, showing the controller for the needle thread in side elevation. Fig. 3 is a detail view showing the needle thread controller at the point where the needle thread is released. Fig. 4 is a detail in side elevation of one of the thread carrying loopers. Fig. 5 is a back view of the same. Fig. 6 is a detail showing one position of the needle and loopers. Fig. 7 is a similar view showing the extreme rear position of the loopers.

In the present embodiment of my invention, the bed plate 1, has rising therefrom, an overhanging arm 2, carrying a needle bar 3 at the forward end thereof. Said needle bar is provided with a needle 4, and receives its oscillation from a needle lever 5, pivoted at 6 to the overhanging arm. Said needle lever 5 is connected in the usual way to the needle bar by means of a link 7. The needle lever 5 is oscillated by means of a link 8, which co-operates with an eccentric on the main shaft 9, which is rotated by the usual belt wheel 10. The needle thread passes from the supply to a thread guiding arm 11 to an eyelet 12 and thence, to a tension device 13 carried by the head of the machine. The thread is then led through an eyelet 14, carried by the needle lever 5, and to a tension device 15, carried by the overhanging arm.

It will be seen, that as the needle lever is vibrated the thread eyelet 14 carried thereby, will engage the thread between the tension devices 13 and 15, and pull a little thread each time, through the tension device 13. The thread after leaving the tension device 15, passes through my improved thread controller 16, to an eyelet 17, which is adjustably secured to the overhanging arm of the machine. Said eyelet 17 is carried by a plate 18, which is slotted at 19 to receive the guide pin 20, and a locking screw 21. The thread passes from the eyelet 17 through the tension device 22, carried by the needle bar 5, and thence to the eye of the needle.

My improved thread controller 16 comprises two thread guides 23, 24, carried by a plate 25 secured to the overhanging arm.

The needle lever 5 carries a base plate 26 to which is adjustably secured a bracket 27, carrying arms 28 and 29. Said arms 28 and 29 are formed with the thread engaging 5 shoulder 30 near the upper end. Said arms above the thread engaging shoulders are tapered as at 31, Fig. 2, so as to readily pass the thread in their upward movement. A thread releasing cam 32 is carried by the 10 overhanging arm, and lies in the space between the thread arms 28 and 29. The operation of my thread controller will be obvious. When the needle lever 5 is vibrated so as to cause the needle to descend, the 15 arms 28 and 29 are brought down with the needle lever. The thread engaging shoulder 30 is brought into engagement with the needle thread passing through the thread guides 23 and 24 and carries the thread 20 downward therewith as shown in Fig. 3. As soon as the thread is carried down by the arms 28 and 29, it is brought into engagement with the releasing cam 32, which crowds the thread off from the thread engaging shoulder 30, thus releasing the thread 25 from the arms 28 and 29. By adjusting the position of the bracket 27, which supports the thread arms 28 and 29, I may thereby vary the time when the thread will 30 be released, and also the amount of thread taken up by said arms.

It will be noted that the arms 28 and 29 lie in the arc of a circle, the center of which is the pivot pin 6 for the needle lever 5. 35 It will also be noted that the cam 32 is similarly curved.

Cooperating with the needle beneath the work support 33, is a thread carrying looper 34, which is mounted on a looper carrier 35, 40 pivoted at 36 to the bed plate. Said looper carrier 35 is vibrated by means of a link 37, which is connected to one arm of a rock shaft 38, pivoted to the standard of the machine. Said rock shaft 38 is connected by 45 means of a link 39 to an extension 40 carried by the needle lever 5. These parts are of the usual construction in this type of overseaming machine, and will not need further description. As the needle is re- 50 ciprocated the thread carrying looper 34 moves forward into the needle loop, and moves to the position shown in Fig. 1. A thread carrying looper 41 is carried by a suitable support beneath the work support 55 and is vibrated by mechanism connected to the main shaft in the usual manner in this type of machine. Said thread carrying looper moves up between the thread running from the previous stitch to the eye of the 60 thread carrying looper 34, and the body thereof. Said looper 41 continues up over the work support to a position where the needle may enter the loop of thread formed by the looper 41. The thread for the looper 65 41 passes from the supply through a thread

guide 42, and thence, to an eye 43 carried by the needle lever extension and moving therewith, so as to pull thread from the supply for said looper. The thread then passes through a tension device 44 and then to an 70 adjustable eyelet 45, carried by the standard of the machine. Said thread is then led through an eyelet 46 carried by the needle lever extension, and moving therewith, and which serves as a take up for the thread of 75 the looper 41. The thread passes from the eyelet 46 to a stationary eyelet on the bed plate and then through the open eye 47 at the heel of the looper 41 to the eye of the looper. The thread for the looper 34 passes 80 from the supply through a suitable guide 48 to the eyelet 49 carried by the needle lever extension 40, which serves as a means for pulling thread from the supply for said looper. The thread then passes through the 85 tension device 50, and is thence, led to a stationary thread guide 51, and from said thread guide to the eye at the heel of the looper 34, and thence, to the eye of said looper. 90

The thread guide 51 as shown in Figs. 6 and 7 is so located that the thread passing from said thread guide to the heel of the looper lies in the path of movement of a lug projecting from the body of the looper 41. Said lug in the present embodiment of my invention is shown as a shank of the open eye 47, although it is obvious that said lug may be entirely independent of this thread eye. 95

The operation of my device is as follows:—When the needle is substantially at its extreme upper position, the thread carrying looper 34 is substantially at its extreme forward position, and the needle loop beneath the work support extends from a previous needle puncture around the looper 34. The looper 41 at this time, extends up through the looper thread loop formed by the looper 34, and is over the work support in position for the needle to enter the loop formed thereby, as it descends. As the needle descends, the thread arms 28 and 29 engage the needle thread, and drawing thereon, pull up the needle thread that is given up by the backward movement of the looper 34, thus drawing some of the slack out of the previously formed stitch. Said thread arms 28 and 29, also at this time draw a little thread through the tension device 15. As soon as the eye of the needle however, nearly reaches the upper surface of the work, the thread is released from said thread arms 28 and 29 by the releasing cam 32. This leaves the needle as the eye thereof is about to enter the fabric with the thread thereof entirely slack, so that said needle eye may pass well through the fabric before said slack is taken up. After, however, the needle has passed well through 105 110 115 120 125 130

the fabric, said slack is consumed and the previous stitch still further tightened by the needle.

I have found in practice that in order to 5 put sufficient tension on the thread in an overseaming machine, so as to make a tight stitch, I must avoid putting strain on the thread at the time the eye of the needle is passing through the material. When the 10 eye of the needle is passing through the material, the thread is put under considerable strain, and if there is any reaving of the thread through the eye at this time, said thread will be broken. If the thread is 15 taut at the time the eye of the needle reaches the material, this reaving of the thread therethrough occurs. After the eye of the needle is entirely through the material, the thread then lies in the groove of the needle, 20 and the binding action of the material on the thread, is released to a certain extent, so that no harm is caused by the thread sliding through the needle eye. By my improved thread controller, the necessary slack 25 is given to the thread at the proper time, so that said thread is entirely free from tension, when the needle eye is passing through the material and I can thereby, greatly increase the tension on the needle 30 thread. As the looper 41 is retracted, it engages the looper thread of the looper 34 just before the loop of said looper 34 is shed from the looper 41, and takes up the slack caused therein, and a further retracting 35 movement of the looper 41 causes the stitch to be drawn tight and causes a certain amount to be pulled through the tension 40 for said looper 34. This thread drawn off by the looper 41, is given up to the looper 40 34, as it moves forward into the needle loop.

The purpose of drawing from the supply a little thread for the looper 34, which is given up to the looper as it moves forward, is so that the needle loops when the stitch 45 is set, will lie in a line coincident with the needle punctures. If the looper thread is slack, the tension on the needle thread will draw the needle loops into the line of the needle punctures, and thus produce a very 50 tight stitch.

I have shown the bracket 27 as connected to the base plate 26 by means of a screw 27^a and a slot 27^b. I have also shown, see Fig. 2, the plate 25 which carries the guides 23 55 and 24 adjustably secured to the overhanging arm 2 by means of screws 25^a, 25^b which pass through slots 25^b in said plate 25.

By adjusting the thread guides 23 and 24 toward or from the shoulder 30 when in its 60 extreme lower position, I can adjust the amount of thread pulled off and the time of releasing the thread will remain the same.

When it is desired to adjust the time of 65 releasing the thread without adjusting the amount of thread pulled off, the bracket 27

is adjusted by loosening the screw 27^a and after this is set so as to release the thread at the proper time, then the thread guides 23 and 24, may be adjusted so that the amount of thread pulled off, will remain the same. 70

Having thus particularly described my invention, what I claim as new and desire to secure by Letters Patent, is:

1. The combination with stitch forming mechanism, including a needle, of means for 75 taking up the needle thread on the first part of the downward movement of the needle, and for giving slack to said needle as the eye thereof enters the material and independent means for taking up the needle thread for setting the stitch.

2. The combination with stitch forming mechanism, including a needle, a tension, means for taking up the needle thread on the first part of the downward movement of 85 the needle, pulling thread through the tension and giving slack to the needle as the eye thereof enters the material and independent means for taking up the needle thread for setting the stitch. 90

3. In an overseaming machine, the combination of a needle and complementary stitch forming mechanism for carrying threads around the edge of the material and a needle thread controller operating to pull up the 95 needle thread on the first part of the downward movement of the needle and to give up slack to the needle just before the eye thereof enters the material.

4. In an overseaming machine, the combination of a work support, a needle, a thread carrying looper coöperating therewith beneath the work support, a second thread carrying looper coöperating with the first thread carrying looper, and with the needle 100 above the work support, a needle thread controller operating to give slack to the needle just before the eye thereof enters the material and means independent of the slack 105 thread controller for taking up the needle thread for setting the stitch.

5. In an overseaming machine, the combination of a work support, a needle, a thread carrying looper coöperating therewith beneath the work support, a second thread 115 carrying looper coöperating with the first thread carrying looper and with the needle above the work support, and a needle thread controller operating to pull up the needle thread on the first part of the downward 120 movement of the needle, and to give up slack to the needle just before the eye thereof enters the material.

6. In an overseaming machine, the combination with a work support, a needle, a 125 thread carrying looper coöperating with said needle beneath the work support, a second thread carrying looper coöperating with the first thread carrying looper and with the needle above the work support and 130

a needle thread controller for taking up the slack in the needle thread on the downward stroke of the needle and releasing the same just before the needle eye enters the material, said needle thread controller including a reciprocating thread engaging member and means coöperating therewith to release the thread from said member.

7. The combination with stitch forming mechanism, including a needle, of means for taking up the slack in the needle thread, and releasing the same just before the needle eye enters the material, including spaced thread guides, a reciprocating arm intermediate said thread guides having a thread engaging shoulder, and a releasing cam for stripping the thread from said shoulder.

8. The combination with stitch forming mechanism, including a needle, a needle lever for reciprocating the same, a thread arm carried by said needle lever and having a thread engaging shoulder, spaced thread guides between which said arm is reciprocated, and means for releasing the thread from said shoulder.

9. The combination with stitch forming mechanism including a tension device, a needle, means for reciprocating said needle, including a needle lever, a thread engaging arm carried by said needle lever, and engaging the thread between said tension and needle, spaced thread guides coöperating with said thread engaging arm, and means for releasing the thread from said thread engaging arm.

10. The combination with an oscillating member, means for oscillating the same, a thread engaging arm carried by said oscillating member and projecting laterally therefrom, said thread engaging arm being curved so as to lie in the arc of a circle, the center of which is the pivotal point of the oscillating member, a stationary member extending at right angles to the plane of movement of said oscillating member and disposed so as to coöperate with said thread engaging arm for stripping the thread from said arm, and thread guides for guiding the thread so as to be engaged by said thread engaging arm as the same oscillates.

11. The combination with an oscillating member, means for oscillating the same, a thread engaging arm carried by said oscillating member and projecting laterally therefrom, said thread engaging arm being curved so as to lie in the arc of a circle, the center of which is the pivotal point of the oscillating member, a stationary member curved to correspond to said curved arm and having a laterally projecting cam for stripping the thread from said arm, and thread guides for guiding the thread so that the same is engaged by said arm during the oscillations thereof.

65 12. The combination of a member, means

for oscillating the same, a bracket carried by said member, parallel spaced thread arms carried by said bracket, each of which is provided with a thread engaging shoulder, said arms being curved about the center of said oscillating member and spaced at different distances from said center, a stationary thread cam located between said arms and operating to release the thread from the thread engaging shoulders and spaced thread guides coöperating therewith, said thread guides lying in the plane of movement of the oscillating member for positioning the thread in engagement with said thread engaging shoulders.

70 13. The combination of an oscillating member, means for oscillating the same, an adjustable bracket carried by said member, parallel spaced thread arms carried by said bracket, each of which is provided with a thread engaging shoulder, said arms being curved about the center of said oscillating member, a stationary thread cam located between the thread arms and operating to release the thread from the thread engaging shoulders and spaced thread guides coöperating therewith.

75 14. In an overseaming machine, the combination of a needle, and complemental stitch forming mechanism for carrying threads around the edge of the material, and a needle thread controller operating to give slack to the needle, just before the eye thereof enters the material, said needle thread controller including a reciprocating thread engaging arm, spaced thread guides coöperating therewith, and means for releasing the thread from said arm.

80 15. In an overseaming machine, the combination of a needle, and complemental stitch forming mechanism for carrying threads around the edge of the material, and a needle thread controller operating to give slack to the needle, just before the eye thereof enters the material, said thread controller including spaced thread guides, spaced thread engaging arms and a cam plate located between said thread arms and stripping the thread from said arms.

85 16. In an overseaming machine, the combination of a work support, a needle, a thread carrying looper coöperating therewith beneath the work support, a second thread carrying looper coöperating with the first thread carrying looper, and with the needle above the work support, and a needle thread controller operating to give slack to the needle just before the eye thereof enters the material, said needle thread controller including a reciprocating thread engaging arm, spaced thread guides coöperating therewith, and means for releasing the thread from said arm.

90 17. In an overseaming machine, the combination of a work support, a needle, a

- thread carrying looper coöperating therewith beneath the work support, a second thread carrying looper coöperating with the first thread carrying looper, and with the 5 needle above the work support, and a needle thread controller operating to give slack to the needle just before the eye thereof enters the material, said thread controller including spaced thread guides, spaced thread 10 engaging arms and a cam plate located between said thread arms and stripping the thread from said arms.
18. In an overseaming machine, the combination of a work support, a needle, a tension device for the needle thread, a thread carrying looper coöperating therewith beneath the work support, a second thread carrying looper coöperating with the first thread carrying looper, and with the needle 15 above the work support, and a needle thread controller operating upon the needle thread between the tension and the needle and adapted to give slack to the needle just before the eye thereof enters the material. 20
19. In an overseaming machine, the combination of a work support, a needle, a tension device for the needle thread, a thread carrying looper coöperating therewith beneath the work support, a second thread carrying looper coöperating with the first thread carrying looper, and with the needle 25 above the work support, and a needle thread controller operating upon the needle thread between the tension and the needle, and adapted to give slack to the needle just before the eye thereof enters the material, 30 said needle thread controller including spaced thread guides, a thread arm for en-
- gaging the thread between said thread guides, and means for stripping the thread 40 from said thread arm.
20. In an overseaming machine, combination of a needle, a work support, a thread carrying looper, coöperating with the needle beneath the work support, a thread manipulating device, coöperating with the needle above the work support, a tension device for the looper thread, and means intermediate the tension device and the looper for pulling thread through said tension device, said 45 means including a thread engaging arm carried by the thread manipulating device. 50
21. An overseaming machine including in combination a work support, a needle, a thread-carrying looper coöperating therewith beneath the work support, a second thread carrying looper coöperating with the first thread carrying looper and with the needle above the work support, a thread 55 controller operating to pull up the needle thread on the first part of the down stroke of the needle, and to give slack to the needle as the eye thereof enters the material, and means operating upon the looper thread of 60 the looper coöperating with the needle beneath the work support, to take up the looper thread and to pull thread from the supply, tension devices for the needle and for the looper threads. 65
- In testimony whereof I affix my signature, in presence of two witnesses. 70
